UNITED STATES PATENT OFFICE.

JAMES P. MARTIN, OF LANCASTER, PENNSYLVANIA, ASSIGNOR TO RAYMOND C. PENFIELD, OF CHICAGO, ILLINOIS.

PIPE-RACK DRIER-CAR.

1,339,119.

Specification of Letters Patent.

Patented May 4, 1920.

Application filed July 18, 1917. Serial No. 181,403.

To all whom it may concern:

Be it known that I, JAMES P. MARTIN, a citizen of the United States, and resident of Lancaster, in the county of Lancaster 5 and State of Pennsylvania, have invented an Improvement in Pipe-Rack Drier-Cars, of which the following description, in connection with the accompanying drawings, is a specification, like letters on the drawings representing like parts.

My present invention is an improved apparatus consisting in a multiple unit pipe rack drier car, intended primarily for use in the drier system illustrated and explained 15 in my copending application, Ser. No. 194,640, filed October 4, 1917.

In the manufacture of clay products, particularly brick, it is necessary to first dry the brick and then to burn the same in kilns 20 of various types. The best type of drier heretofore known has been the steam pipe rack driers, which required large, expensive, permanently built structures with a vast amount of steam pipes forming racks, on 25 which racks the individual brick units had to be placed, either by hand or on short pallets containing five or six brick units, which latter had to be positioned by hand. The constant handling in the necessary use of 30 such a steam pipe rack drier, both loading and unloading by hand, and the large plant and building necessary, has been a serious difficulty in using this type of drier. My present invention obviates the former difficulties of such steam pipe driers while utilizing all the advantages incident thereto, and providing a movable drier unit, which could be advantageously employed 35 in a car, and used in a waste heat drier, a tunnel drier, railroad kiln drier, or the like.

My pipe rack drying truck or car combines in an ideal manner the numerous advantages of a unit and car system of handling clay products, directly from the brick 45 making machine to a drier, each car being capable of independent connection with a source of steam supply or of being connected to each other, in a train, either of a few cars; or of being connected 50 in a continuous train, such as in a tunnel drier, said cars being thereafter delivered to the kiln shed for burning. My novel idea of a steam pipe rack drying car enables the 55 novel arrangement of my said copending application in an entire manufacturing

plant, and as the individual pipe rack car is an important feature of said system and a distinct novelty, I wish to claim the same broadly.

Referring to the drawings, illustrating a 60 preferred embodiment of my invention, Figure 1 is a plan view of the car; Fig. 2 is a side view; and Fig. 3 an end.

As shown in the drawings, my individual 65 drier car consists in a plurality of pipe shelves adapted to receive the pallets containing the brick to be dried. The car herein shown is of sufficient width to receive pallets of brick from each side, the pipe 70 being arranged in shelf sections at each side of the car. The car consists in a pair of bottom frames 1 and 2, preferably iron I-beams, having cross beams 3 and 4 adjacent either end, which frame has sets of 75 journal bearings 5, 5, to carry the axles 6 for the car wheels 7, 7. The bottom of the frame is preferably open, although the cross brace 8 may be provided with reinforcing straps 9, 9. Upon the frame, at either end, 80 is an upright brace, that shown at 10 being relatively heavy and bolted to the lower framework, carrying the steam pipe manifolds 11 and 12; at the other or expansion end of the car is the upright brace 13, which 85 preferably is reinforced by straps 14 downwardly to the projecting ends of the I-beams 1 and 2. Across the top of the car are straps 15, 15, and side braces 16, 16, giving a firm, strong, open framework. The 90 upright braces 10 and 13 are perforated, the upright 13 having a plurality of pairs of perforations or openings, as illustrated at 14, 14, and 16, 16, these being substantially 95 in tiers at either side of the car, as clearly shown in Fig. 3. Through these openings the ends of the steam pipes 20, 20, project, short elbows 21, connecting each pair of pipes with a suitable piece 22 of appropriate length, all being threaded together, 100 as is customary. At the manifold end of the car, a single set of perforations, as shown at 23 and 24, are provided, the vertical manifold pipes 11 and 12 being threaded to receive the respective ends of the outer 105 pipes in the drier. Either a manifold 11 or 12 can be utilized as for the receiving or incoming steam, while the other will be for the outlet, both receiving and outlet connections being thus made at the same end 110

- of the car. This feature is of a particular value in the saving of time and labor, as well as in enabling adjacent cars to be quickly coupled, when desired.
- 5 It will be seen that the steam being admitted at the manifold 11, for example, flows through each one of the pipe racks, throughout the entire height of the car, at substantially equal heat and pressure, giving a uniformity of heat from the lowermost rack to the uppermost. The steam will thus flow through the pipe 20 in each tier, from the manifold 11 toward the expansion end, around through the elbow 21 and short connecting pipes 22 through the adjacent elbow 22 and the parallel section of pipe backwardly to the manifold end, and then return to the expansion end and backwardly to the outlet manifold 12. The expansion of each pipe 20 is readily taken up by the slidable movement promoted between the pipe 20 and the recesses therefor in the rack 31, without undue strain, without binding, or other difficulty, and without in any way loosening the steam pipe joint in the elbows 21. The car can be run in adjacent the dump table by the brick making machine, the steel pallet with its load of brick slid onto the shelves formed by the pipes 20, until the car is full, then the car is wheeled on to the drier, steam pipe connected, and drying completed, whereupon the steam pipe is disconnected and the car wheeled to the kiln where the brick are stacked for burning.
- When it is appreciated that in steam pipe driers, as heretofore constructed, long permanent buildings were required, with permanent supports for the piping, and separate conveyers to take the brick from the dump table to the different points throughout the drier, and a constant hand labor both at dump table, conveyer and drier, both when loading and unloading, the im-

portance of my invention will be manifest. 45 Furthermore, my car can be utilized in a tunnel drier, conserving heat, reducing labor to a minimum, preserving a continuous system or method of operation, and standardizing brick manufacture. 50

My invention is further described and defined in the form of claims as follows:

1. A multiple pipe rack drier car of the kind described, comprising a truck, a plurality of horizontally arranged steam pipe racks, forming shelves, each rack comprising a plurality of pipes, a vertically extending manifold for said pipes at one end of the car, means permitting independent expansion and contraction for the pipes forming each shelf, and supply and exhaust means for the circulation of steam through the pipes in each rack. 60

2. A multiple pipe rack drier car of the kind described, comprising a truck, a plurality of horizontally arranged steam pipe racks, each rack comprising a plurality of pipes, a vertically extending manifold for said pipes at one end of the car, a support at the other end of the car for said pipes, 70 permitting independent expansion and contraction for the pipe in each shelf, and supply and exhaust means for the circulation of steam through all the pipes in every rack. 75

3. A multiple pipe rack drier car of the kind described, comprising a truck, a plurality of horizontally arranged steam pipe racks, supports for said racks permitting expansion and contraction of the piping in 80 each rack, and vertically extending supply and exhaust manifolds adjacent one end of the truck to provide for the circulation of steam through all the piping in each rack.

In testimony whereof I have signed my 85 name to this specification.

JAMES P. MARTIN.
